[57] CLAIM

The ornamental design for a canvas edge holder for an artist's easel, as shown and described.

DESCRIPTION

FIG. 1 is a perspective view from the left side, top and rear of a canvas edge holder for an artist's easel, showing my new design;

FIG. 2 is a bottom plan view thereof;

FIG. 3 is a front elevational view thereof;

FIG. 4 is a right side elevational view thereof;
FIG. 5 is a perspective view from the left side, top and rear of a modified form of the canvas edge holder for an artist's easel shown in FIG. 1;

FIG. 6 is a bottom plan view of FIG. 5; and,

FIG. 7 is a right side elevational view of FIG. 5.

FIG. 1

FIG. 2

FIG. 3

FIG. 4

FIG. 5

FIG. 6

FIG. 7
